BENJAMIN OLDFIELD AND EDWIN OLDFIELD, OF NEWARK, NEW JERSEY.

Letters Patent No. 73,374, dated January 14, 1868; antedated January 4, 1868.

IMPROVEMENT IN LOOMS.

The Schedule referred to in these Letters Patent and making part of the same.

TO ALL WHOM IT MAY CONCERN:

Be it known that we, BENJAMIN OLDFIELD and EDWIN OLDFIELD, both of Newark, in the county of Essex, and State of New Jersey, have invented a new and useful Improvement in Looms; and we do hereby declare that the following is a full, clear, and exact description thereof, which will enable those skilled in the art to make and use the same, reference being had to the accompanying drawing, forming a part of this specification, in which—

Figure 1 represents a sectional front elevation of this invention, the line $z z$, fig. 2, indicating the plane of section.

Figure 2 is a plan or top view of the same.

Figure 3 is a sectional side elevation of the harness-motion, the line $y y$, fig. 2, indicating the plane of section.

Figure 4 is an end view of the same, showing the harness-motion.

Figure 5 is a similar view thereof, showing the shuttle-motion and the stop-motion.

The remaining figures are details, which will be referred to as the description progresses.

This invention relates to certain improvements in the shuttle, the shuttle-motion, the batten, and the harness-motion, which improvements are applicable to looms of any description, but particularly to such looms on which a number of pieces are woven simultaneously.

The shuttle S is constructed, by preference, of metal plates A, which are united by solder or other suitable means, whereby the weight of the shuttle and the cost of its construction are materially reduced. If desired, however, our shuttle may be made of wood or any other suitable material, and its cheek-pieces, a, are provided with bearings to receive the centres, on which the reel R turns, in contradistinction to shuttles of the ordinary construction, in which a long quill is used, which is secured in the end of the shuttle.

From the ends of our shuttle S project pins b, which may be square or round, and which serve to support the shuttle either in a horizontal or in an upright position. By using these pins we are enabled to dispense with the grooves and tongues generally used in shuttles of looms on which a number of pieces are woven simultaneously, and the construction of the shuttle and that of the batten is materially cheapened and simplified. The pins b are made hollow, so as to receive the tension-spring c, which bears on the surface of the thread wound on the reel. By these means said tension-spring is readily applied, it can be easily changed to suit the nature of the work to be produced, and it regulates itself automatically when the loom is in operation, according to the varying diameter of the roll of thread wound on the reel.

In combination with the tension-spring c, we have applied a brake, c², which acts on the circumference of the reel, and which also overlaps the top edge of the reel, and prevents it being thrown off from its seat. This brake is absolutely necessary, if the reel is made large enough to be of any advantage, and by its action the reel is prevented from flying round too far when the loom is worked fast. With the ordinary tension-spring alone, we have not been able to accomplish this object, and we have only succeeded to produce clear and even edges on the fabric to be woven, by applying the brake in combination with the tension-spring. It will be noticed that the action of the brake bearing on the circumference of the reel is uniform, while that of the tension-spring bearing on the variable diameter of the roll of thread wound on the bobbin, regulates itself according to the varying diameter of said roll.

The reel R is inserted between the cheek-pieces of the shuttle, one of which is provided with a movable or elastic bridge-piece or spring-catch, d, whereby the operation of inserting and removing said reel is materially facilitated. The shape of the shuttle is tapering from the eye towards its back, so that the reel can be readily put in or taken out from the back of the shuttle, the cheek-pieces preventing the reel from being lifted out of place and coming in contact with the warp, (see Figure 8.) If desired, the bridge-piece may be made to act as a brake in combination with a tension-spring of any desired construction. The reel R takes the place of the long quill generally used in shuttles for looms, and on it is wound the weft-thread, which is carried by the shuttle through the warp, and which serves to produce the selvedges on both edges of the fabric to be woven. By using the reel in place of the quill, a large quantity of thread can be put in the shuttle, and consequently the number of stoppages on the loom is decreased, and through the increased diameter of the reel, and its position in the shuttle in connection with the shuttle-eye, the drag on the eye is prevented, and the thread is less liable to get

broken, thus producing a superior fabric, both in quality and in quantity. As the shuttle passes through the shed of the warp, the weft-thread is drawn off from the reel precisely in the same manner as it is drawn off from the long quills in ordinary shuttles.

It will be readily understood that a shuttle constructed as above stated, may be worked either horizontally or in an upright position, and two or more shuttles can be placed one above or behind the other. The top flange of the reel is pierced, as clearly shown in Figure 6, so that the quantity of thread wound on said reel can be ascertained, and the time when a fresh supply of thread is required can be readily determined. The shuttle-eye y^2 is oblong in a direction parallel to the axis of the reel, so that the thread, in passing through said eye, is free to accommodate itself to the spot on the reel from which it unwinds, and any undue friction of the thread, as the same passes through the eye, or any tendency to raise the reel from its seat by the strain of the thread, is prevented. The tension of the weft-thread is regulated by the spring e , as previously described.

The pins b , which extend from the ends of the shuttle, fit into shuttle-carriers C , which are provided with suitable sockets e , to receive the same, and these shuttle-carriers are provided with loose pegs f , which rise and fall by the action of cams g at the proper intervals, and which, as they rise, catch in suitable sockets or cavities in the pins b , (see Figure 12); instead of making the shuttle-carriers with sockets to receive the pins b , they may be made as shown in Figure 13, and in this case they are adapted for shuttles of the ordinary construction, and the pegs f^* may be made cross-shaped, to prevent the shuttle from tipping down. The shuttle-carriers move back and forth on guide-bars h , which are secured in the top of the batten, as shown in figs. 1 and 2 of the drawing, and motion is imparted to said shuttle-carriers by slide bars D , to which they are rigidly attached.

The side bars are situated on opposite sides of the guide-bars, and they move back and forth without rise and fall. Their motion is produced by cog-wheels E , which gear in teeth i , cut in the edges of the slide bars, and which are mounted on a shaft, j , to which an oscillating or rocking motion is imparted by suitable mechanism, which will be hereinafter more fully described. The rack-teeth i and cog-wheels E , take the place of the cords and pulleys generally used for the purpose of imparting motion to the shuttles in looms on which a number of pieces are woven simultaneously.

On the side of each of the cog-wheels E , and firmly attached thereto, or mounted on the shaft j , are cams F F , and these cams act against stops k , secured to the outer surfaces of the slide bars D . Said cams are so shaped, that by their action on the stops k , each slide bar is locked until the proper time arrives for it to move. By this arrangement the pins b of the shuttles are enabled to enter the sockets of the shuttle-carriers without fail, and said shuttle-carriers are firmly retained in position until the pins of the shuttles have passed into them to the required distance.

The motion of the shaft j is produced by a chain, l , which extends over a chain-wheel, m , mounted on said shaft, and made to pass under a pulley or drum, n . This pulley or drum is mounted on a shaft, o , to which a rocking motion is imparted by what is technically known as a "Marionette"-motion, or by any other equivalent mechanism. In looms of the ordinary construction, the "Marionette-motion" connects directly with the shuttle-motion, and the speed of the shuttles cannot be regulated. By interposing the speed-pulley n between the "Marionette-motion" and the shuttle-motion, we are enabled to regulate the speed of the shuttles simply by increasing or decreasing the diameter of said pulley, so that the speed of the shuttles can be reduced to the smallest possible point, enabling them to clear the work, and the speed of the loom may be increased in proportion.

With the shuttle-motion of our loom we have combined a stop-motion, the action of which is based on a rising and falling spring-stop, s , which is depressed by a cam or eccentric, t , mounted on the shaft j . If the shuttle-motion works correctly, the depression of the spring-stop takes place at such intervals that the same will clear the shoulder or offset u in the bar E' . This bar is supported by slotted brackets F' , in which it is permitted to slide back and forth, and it is provided with a hook, v , which catches in a hole in the spring-lever w . If the hook v is made to release this spring-lever, it follows the action of its spring, and causes the belt-shipper H to move in the direction of the arrow marked on it in fig. 2, and by this movement of the belt-shipper, the driving-belt is thrown from the fast pulley I on the loose pulley I' , and the motion of the loom stops. If the shuttle-motion works correctly, the spring-stop s is depressed when the batten or lay is at the backward end of its stroke, and in this case, said stop does not come in contact with the shoulder u , but if the shuttle-motion from some reason becomes deranged, said spring-stop is depressed during the forward stroke of the batten or lay, and striking the shoulder u , it causes the bar E' to move in the direction of the arrow marked on it in fig. 1, and the hook v is immediately made to release the spring-lever w , causing the loom to stop before the shuttle comes in contact with the fabric.

The stop-motion is rendered still more effective by a brake, G , formed by an arched strap, a' , which extends over the fast pulley, and which is made to bear on the surface thereof, whenever the spring-stop strikes the shoulder u .

The batten B ; instead of being secured directly to the ends of the swords as usual, is combined with a parallel-motion, P , which may be composed of four hinged-levers p , four links q , and two connecting-rods r , or which may be constructed in any other suitable manner. By the action of this parallel-motion the batten is made to move in a horizontal plane, or nearly so, and thereby friction in the warp-threads is prevented, and the openings of the shed can be reduced.

The pulleys I I' are mounted on the main shaft K , which has its bearings in suitable boxes in the main frame of the loom, and on the end of this shaft, opposite to said pulleys, is secured the bevel-wheel U' , which gears in a similar bevel-wheel, U , on the end of a shaft, d' , which has its bearings in suitable arms or brackets secured to the main frame of the loom.

On the shaft d' is mounted an oval wheel, e' , which gears in a correspondingly oval wheel, f' , mounted on a shaft, g' , which has its bearings in suitable arms or brackets, or in the side pieces of a frame, J , which supports the principal mechanism of the harness-motion. This harness-motion is composed of arms L , each of which is attached at one end to a long lever, M , and operated by a circular or segmental chain-wheel, N , or any equivalent device, as will be presently explained.

In the drawing, chain-wheels are shown, to which an oscillating motion is imparted by means of chains h' , which pass over said chain-wheels, and from the ends of which rods i' are suspended. These rods pass through slots in arms or vibrators j' , which project from a rock-shaft, k' , and bear against the pattern-chain, and said rods are provided with hooks, l' , which are hinged, and so arranged that they can swing back, but they are not allowed to swing inwardly or towards each other beyond a certain point, as seen particularly in fig. 3 of the drawing.

Between the rods i' and hooks l' extends the knife O , which moves up and down on vertical guide-bars m' , and to which motion is imparted by rods n' , which extend from its ends to eccentric wrist-pins o' , secured in disks p' . These disks are mounted on the shaft g' , which receives an irregular revolving motion by the oval wheels $e' f'$, and, by this irregular motion of said shaft, the harness-motion is so timed that the warp-threads are exposed to the least possible strain, and, consequently, the speed of the loom can be increased.

As the knife O passes up, the hooks l' are pressed back, but when the knife descends, it catches into such of the hooks as are brought in the proper position by the pattern-chain, and the corresponding heddles are raised or depressed. This motion is effected as follows: Each heddle-frame is suspended by cords or wires from elbow-levers q' , which have their fulcra on suitable cross-bars or pins in the top rail of the loom, and which also connect, by suitable cords or wires, with the top ends of the long levers M , as already shown in fig. 1 of the drawing. From the under edges of the heddle-frames extend cords or wires round pulleys r' , in the bottom part of the loom, and these cords or wires are attached to the lower ends of the long levers M . Each of these long levers connects with one of the chain-wheels N , and from each chain-wheel are suspended two rods, i' , one on either side of the knife O , as shown in fig. 3. These rods pass through their slotted arm or vibrator, j' , and if this arm or vibrator is pressed back by the action of the pattern-chain, as shown in said figure, the knife O , in descending, catches in the hook of the outer rod i' , and the chain-wheel N is turned in the direction of the arrow, marked thereon, in fig. 3. By this motion of the chain-wheel, the arm L , attached thereto, is caused to move in the direction of the arrow marked on it, and the heddle-frame attached to its long lever is raised. If the pattern-chain revolves, and the slotted arm j' is permitted to move out in the direction of the arrow marked thereon, the hook attached to the inner rod i' is brought in such a position that the knife, on its subsequent descent, will catch in the same, and thereby said inner rod will be carried down, and the heddle-frame, attached to the long lever M , is depressed.

It is obvious that, by these means, each heddle-frame can remain in an elevated or depressed position for any number of picks, as indicated by the pattern-chain, and said heddle-frames are not permitted to descend or rise until the corresponding slotted arms or vibrators j' are permitted to drop.

If desired, a suitable locking-device, such as a weak spring or brake, may be applied to the long levers, to counterbalance the weight of the heddle-frames, and to keep the same up or down, as long as may be required, by the pattern-chain.

If desired, the chain-wheels N might be replaced by cog-wheels or toothed segments, and, in this case, the upper ends of the rods i' would have to be formed into toothed racks, or said rods would have to be connected to toothed racks.

The arms L , instead of being pivoted to the chain-wheels, might be provided with cogs in either edge, which could be made to gear in cog-wheels or pinions attached to the sides of the chain-wheels, or mounted on the same shaft with said chain-wheels, and close to the same. All such changes we would consider equivalents to the devices previously described, and represented in the drawing.

The pattern-chain Q is constructed in the ordinary manner, with the exception that the pins or studs r are secured in the same in such a manner that they can be readily put in or removed by pressure. This object is effected by placing, under said pins or studs, elastic cushions, s' , so that, after the T-shaped shanks of the same have been introduced through the slots t' , in the leaves of the pattern-chain, (see Figure 11,) and turned so as to bring the heads of the shanks at right angles to the slots, the elastic cushions will force said heads into recesses u' , on the inner surfaces of the leaves, and the studs or pins are firmly held in position. By depressing one of the studs against the elastic cushion, until the head of its shank clears the recess at the inner surface of the leaf, said stud or pin can be turned and removed. By these means, the operation of inserting and removing the studs is rendered easy, and the pattern-chain can be changed with little trouble or loss of time.

What we claim as new, and desire to secure by Letters Patent, is—

1. The combination of a brake, c' or d , with the tension-spring c , reel R , and shuttle S , substantially as and for the purpose set forth.
2. The spring-catch or bridge-piece d , in combination with the shuttle S and reel R , constructed and operating substantially as and for the purpose described.
3. The loose peg f , in combination with the shuttle-carriers C , guide-bars h , cams g , and shuttle S , constructed and operating substantially as and for the purpose set forth.
4. The arrangement of slide bars D , moving on the top of the batten, in a straight line, without rise and fall, having uprights attached thereto with holes in to receive a loose peg or stud capable of carrying a shuttle, each peg or stud receiving motion by a cam or its equivalent, substantially as and for the purpose set forth.

5. The arrangement of cams F, attached to or formed by the cog-wheels E, in combination with stops k on the slide bars D, substantially as and for the purpose described.
6. The arrangement of a cam and eccentric, t, attached to and operated by the shaft that carries the shuttle-actuating devices, and, in combination therewith, the spring-stop g, bar E', and belt-shipper H, constructed and operating substantially as and for the purpose set forth.
7. The arrangement of a brake, G, in combination with the stop-motion and shuttle-motion, constructed and operating substantially as and for the purpose described.
8. Operating the harness by chains and chain-wheels N, and levers L M, substantially as and for the purpose set forth.
9. A harness-motion, composed of loose arms L, each of which is pivoted at one end to a lever, M, and at the opposite end to a circular or segmental chain-wheel N, substantially as and for the purpose described.
10. The vibrators j', in combination with the rods i', carrying the hooks l', and with the intervening knife O and pattern-chain Q, constructed and operating substantially as and for the purpose set forth.
11. The arrangement of elastic springs or cushions under the pins or studs of the pattern-chain, in combination with the T-headed shanks of said pins or studs, and with suitable ridges or cavities on the inner surfaces of the several leaves of the pattern-chain, substantially as and for the purpose described.
